Filed July 8, 1959, Ser. No. 56,705

Term of patent 7 years

(Cl. D52—3)

FIG. 1

FIG. 3

Fig. 1 is a front elevational view of an envelope deposit box for parking meter stands, showing my new design. Fig. 2 is a side elevational view of same. Fig. 3 is a top plan view of same.

The undisclosed side of the deposit box is plain in appearance.

The fragmentary broken line portion of a post is shown for illustrative purposes only.

I claim:

The ornamental design for an envelope deposit box for parking meter stands, or the like, as shown and described.
